UNITED STATES PATENT OFFICE.

WILLIAM HORNING, OF JOHNSTOWN, NEW YORK.

DESIGN FOR A THILL-CO尤LING SPRING.

SPECIFICATION forming part of Design No. 30,203, dated February 14, 1899.

Application filed October 22, 1898. Serial No. 894,347. Term of patent 14 years.

To all whom it may concern:

Be it known that I, WILLIAM HORNING, a citizen of the United States, residing at Johnstown, in the county of Fulton and State of New York, have invented and produced a new and original Design for Springs for Thill-Couplings, reference being had to the accompanying drawings, forming part thereof.

Figure 1 is a side elevation of the spring of my new design. Fig. 2 is a top plan thereof.

As shown, the leading features of my design consist in a body provided with arms 2 3 of unequal length, connected by a bend or

curve 4, creating a cam-spring of substantially U shape, and eyes or tubular bearings 15 5 upon the free end of each arm.

What I claim as new, and desire to secure by Letters Patent, is—

The design for a thill-coupling spring, as herein shown and described.

In witness whereof I have hereunto set my hand this 17th day of October, 1898.

WILLIAM HORNING.
